Primary Examiner — Jack Reickel*Assistant Examiner* — Bobby W Jones, II(74) *Attorney, Agent, or Firm* — Foley & Lardner LLP(57) **CLAIM**

We claim the ornamental design for an oil filter, as shown
and described.

DESCRIPTION

FIG. 1 is a front perspective view from above of the claimed
oil filter;

FIG. 2 is a front perspective view from below of the claimed
design of FIG. 1;

FIG. 3 is a front view of the claimed design of FIG. 1;

FIG. 4 is a rear view of the claimed design of FIG. 1;

FIG. 5 is a left side view of the claimed design of FIG. 1;

FIG. 6 is a right side view of the claimed design of FIG. 1;

FIG. 7 is a top view of the claimed design of FIG. 1; and,

FIG. 8 is a bottom view of the claimed design of FIG. 1.

One exemplary use of an oil filter embodying one or more
of the ornamental designs shown or described herein is as an
oil filter for use in a small internal combustion engine
suitable for powering a lawn mower or other outdoor power
equipment.

Any portion of the article depicted in broken lines forms no
part of the claimed design.
